(57) **CLAIM**

The ornamental design for a tote, as shown and described.

DESCRIPTION

FIG. 1 is a top, front and right side perspective view of the tote in accordance with the first embodiment of our design.

FIG. 2 is a left side elevational view thereof.

FIG. 3 is a right side elevational view thereof.

FIG. 4 is a bottom plan view thereof.

FIG. 5 is a top plan view thereof.

FIG. 6 is a front elevational view thereof; and,

FIG. 7 is a rear elevational view thereof.

The broken lines showing handles and decorative tassel are for the purposes of illustrating environment and forms no part of the claimed design.
